SERVICE T

Elting Henderson, Whittier, Calif.

Application June 29, 1942, Serial No. 448,979

2 Claims. (Cl. 251—43)

The present invention relates to an improved service T arranged to be interposed between a fluid pressure main and a branch or service pipe, for conducting gas, water, oil, and other fluids from the main to the service pipe, and is more particularly directed to the association with the service T, of a combined plugging unit and tool guide. The present application is a continuation-in-part of my copending application Serial No. 410,632, filed September 12, 1941.

An important feature of the invention consists in providing the bore of the T with an integral web or partition member which is formed with a reduced axially disposed opening of such length and diameter relative to the drill or a center locating punch, that the wall of the reduced opening acts to constitute an axially disposed guide to insure both the drill tool and the punch, when inserted into the T, being maintained in proper operative alignment relative to the part of the main to be tapped. The wall of the opening in the web also coacts with the drill to prevent the latter from crawling on the main during the drilling operation. The top or upper surface of the web is formed to provide a seat for the end of a movable plug or stopper which is permanently inserted within the T after the drilling operation is completed. This plug is normally adjustably maintained in a position above the web so as not to interfere with the free flow of the fluid through the T. However, in the event it becomes necessary to cut off the supply to the service line or pipe, this may quickly and easily be done by moving the plug in engagement with its seat.

A further object is to provide an improved apparatus for controlling the flow of the fluid through the T. This is effected by associating with the valve seat in the T, means including a hollow plug or cylinder having its inner and outer surfaces provided with threads of different pitch, which coat with complementary formed threads on the inner wall of the T and the outer surface of the stopper, to move the stopper axially relative to its seat. The differential threaded plug is also arranged when rotated relative to the stopper when the latter is initially moved against its seat, to exert an increasing downward pressure on the stopper due to the difference in pitch of the threads, to insure the stopper being maintained in tight sealing engagement with its seat when the fluid supply is cut off.

Other objects and advantages of the invention will become apparent from the following description, when taken in conjunction with the accompanying claims and drawing.

Referring to the drawing, in which are shown several preferred embodiments of the invention:

Figure 1 is a vertical sectional view of the T and the main to which it is applied, and shows a part of a drilling tool associated therewith.

Figure 2 is a vertical sectional view of the T showing a plugging unit associated therewith.

Figure 3 is a detail vertical sectional view of the upper portion of the T showing the stopper in its raised position.

Figure 4 is a plan view of Figure 3.

Figure 5 is detail vertical sectional view of a modified form of the invention, and

Figure 6 is a plan view of Figure 5.

Referring to the drawing, in which like numerals indicate like parts in the several views, 10 designates the body of a service T which is connected to the fluid pressure main 11, such as a gas pipe or the like, in any suitable manner, such as by having its lower or inlet end welded as at 12 to the main. Prior to the connection of the T 10, it is preferably preformed with an axial bore 13 and a lateral port or outlet 14 to which the service line or pipe, not shown, is suitably connected.

The T 10 may be of solid steel forging and is bored inwardly from each end thereof a specified or predetermined distance, to form the elongated integral web or partition 15, which preferably extends from the lateral port 14 downwardly to a point adjacent the main 11 to provide the bore with a lower or inlet section 16 and a spaced upper section 17. The solid web 15 is then drilled to provide the reduced axially disposed elongated opening 18 so as to establish communication of the inlet section 16 with the upper section 17 and the outlet port 14. The upper end of the T 10 has an externally threaded portion 19 and an internally threaded portion 20.

The preformed T 10 is initially installed at the point where the branch line or service pipe is to be attached to the main, and a drilling apparatus such as shown in the Mueller Patent No. 1,996,845, April 2, 1935, may then be connected to the T in order to tap the main. The fitting 21 of the drilling apparatus is internally threaded at its lower end so as to be connected as at 22 to the externally threaded portion 19 of the T. The elongated drill 23 which is connected as at 24 to the rotatable operation rod 25, is then inserted through the fitting 21 and into the T to form the opening 26 in axial alignment with the bore 13. The reduced opening 18 preferably extends from the outlet 14 to a point adjacent the inlet of the bore, and is

of such a length as to overlap a major portion of the tool inserted therein, in order to serve as a guide to hold the shank of the tool steady during the drilling operation.

The reduced opening 18 in the web 15 is accurately machined or formed to provide a small tolerance or clearance between the wall thereof and the drill. It will be manifest that if there is too much clearance between the drill and the wall of the opening 18, the wall would not constitute a guide means or bearing surface which would insure proper alignment of the tool with the main during the tapping operation. For this reason, the clearance between the tool and the wall of the opening 18 should not be over .010". Heretofore in devices of this character, no means has been provided to prevent the drill from crawling on the main, and, as a result, the drill not infrequently has been broken in the T due to the excessive strains to which it was subjected during the drilling operation. By virtue of the small clearance between the wall of the opening 18 and the drill, it will be seen that positive, efficient and economical means are provided for guiding and maintaining the drill in proper alignment with the T when drilling a hole in the main and which also prevents crawling of the drill on the main. The upper surface of the web 15 at the juncture of the section 17 with the reduced opening 18, is preferably formed with a seat or tapered portion 27, the purpose of which will be subsequently described.

Prior to the attachment of the drilling apparatus to the T to tap the main 11, a center locating punch such as shown in the Mueller application, Serial No. 315,825, filed January 26, 1940, may be introduced into the T to form an indentation in the outer wall of the main to insure the opening 26 being formed concentric with the bore of the T. The diameter of the centering punch is substantially the same as that of the drilling tool 23 so that the wall of the reduced opening 18 will insure the punch being maintained in proper axial alignment with the bore of the T. Upon the removal of the punch or indenting tool from the T, the fitting 21 and its associated parts are connected to the upper portion of the T so that the drill 23 may be rotated and moved axially into engagement with the indented portion of the main, and thus insure the drill 23 being positioned and maintained concentric with the drilling apparatus and the bore of the T during the tapping operation.

After the opening 26 is formed in the main, the drilling apparatus is removed from the T and a plugging unit is permanently positioned within the upper section 17 of the bore. This plugging unit comprises a hollow removable closure member or brass plug 28 which is externally threaded, as at 29, to engage the complementary internal threads 20 on the T. The closure member 28 also has an internally threaded opening 30 concentrically disposed relative to the axis of the bore 13 of the T. The wall of the opening 30 is arranged to receive and guide the upper threaded portion or stem 31 of an adjustable stopper or plug 32, preferably made of steel, and which is inserted within the T after the opening 26 has been formed in the main, in order to provide means for controlling or cutting off the flow of the fluid supply from the main to the service pipe when it is desired to inspect, repair or replace the lat-

ter. The stopper 32 is relatively short and is preferably formed with a tapered lower end portion 33 arranged to extend a limited distance within the opening 18 of the web and engages

5 the seat 27 when it is necessary to cut off the flow of the supply of the surface line so as to form a tight sealing engagement therewith. The top of the stem or portion 31 of the stopper 32 may be provided with a kerf or recess 10 34 which receives a suitable tool, such as a screw-driver or the like, so as to control the axial position of the stopper 32 relative to the seat 27. The stopper 32 is preferably formed beneath the threaded stem 31 with a tapered 15 shoulder 35 arranged, when the stopper is raised to its full open position, to engage the lower end of the opening 30 in the plug 28 (Fig. 3) in order to prevent leakage of the fluid therethrough. The upper end of the plug 28 extends from the T and has a reduced portion or head 36 of any polygonal shape for receiving a tool such as a wrench, so as to apply or remove the plug from the T.

When the stopper 32 is moved downwardly 25 against its seat 27 to cut off the flow of gas through the T, it has been found that it is not possible to apply sufficient pressure on the stopper by a screw-driver inserted in the kerf 34, effectively to seal the gas flow through the T.

30 Accordingly, the threads 20 and their coacting threads 29 on the plug 28 are of different pitch than the threads 30 and their coacting threads 31 on the stopper 32. As shown in Figure 2, the threads 20-29 are 14-pitch, while the threads 35 30-31 are 13-pitch. The internal threads on the plug 28 and their coacting threads on the stem of the stopper 32 may be of greater or less pitch than the external threads on the plug and their coacting threads on the T.

40 When it is desired to cut off the flow of the gas through the T, the stopper 32 is rotated clockwise as shown by the arrow A in Figure 4 so as to be forced downwardly as tightly as possible against its seat 27 by a screw-driver or the like, 45 inserted in the kerf 34. This pressure alone would not be sufficient to insure the stopper being maintained in sealing engagement with its seat. Therefore, a suitable tool, such as a wrench, is applied to the head 36 of the plug 28

50 to back up or turn the latter in a counterclockwise direction (arrow B, Figure 4), which tends to unscrew the plug 28 from the T 10 at the rate of $1/14$ " per revolution. Since the internal threads 30 and their coacting external threads 31

55 on the stem are $1/13$ " pitch, it will be seen that, due to the differential effect of the pitch of the threads 20-29 and 30-31, the plug 28 will tend to come off or be removed from the stopper 32 at a faster rate than it can be unscrewed from

60 the T 10, with the result that the plug 28 exerts a downward increasing thrust or pressure on the stopper 32 equal in effect to a fine thread, the equivalent of the differences in the pitch of the threads 20-29 and 30-31. Thus, positive

65 means are provided to insure the stopper being held against its seat irrespective of the pressure of the fluid in the main. Moreover, since the head 36 of the plug 28 may be engaged by a wrench or other tool having a good leverage, a much greater force can be exerted on the stopper to insure the latter being moved and maintained in tight sealing contact with its seat 27.

In the modification shown in Figures 5 and 6, the pitch of the threads are reversed to that previously disclosed. In other words, the external

threads 37 on the plug 38 and their complementary internal threads 39 on the inner wall of the T 40 are of 13-pitch, while the internal threads 41 of the plug and their coacting external threads 42 on the stem of the stopper 43 are of 14-pitch.

To cut off the flow of the fluid from the T 40, the stopper 43 is initially turned in the direction of the arrow C (Figure 6) so as to be forced in engagement with its seat, by a tool inserted in the kerf or opening 44 sufficiently tight so as not to be rotated when the plug 38 is moved relative thereto. After the stopper has been seated, a suitable tool is applied to the head 45 of the plug 38 and the latter is rotated in a clockwise direction or the same direction in which the plug has been turned, as shown by the arrow D in Figure 6, to engage its seat, in order to exert a downward increasing pressure on the stopper due to the difference in pitch of the threads, and thus insure the stopper being firmly maintained in sealing engagement with its seat. It will be noted that the only substantial difference between the threaded arrangement shown in the form of the invention disclosed in Figure 5 from that shown in Figure 2, is that in the former the plug is rotated in a counterclockwise direction, or opposite to the direction of rotation of the stopper while in the latter it is turned in the same direction to force the stopper against its seat.

In both forms of the invention, the flow of the fluid through the T is controlled by, first, threading the stem of the stopper to the plug, then inserting the plug and stopper into the T so that the plug is threaded to the T above the valve seat. While, normally, the stopper is moved away from its seat to allow the free flow of the fluid through the T, it will be seen that upon the stopper being moved downwardly by a suitable tool, it will be brought into sufficiently tight engagement with its seat, as to be prevented from rotating with the plug when the latter is turned to increase this downward pressure. The plug is then either turned in the same direction or in the opposite direction to that of the stopper, depending upon the pitch of the threads, and is moved relative to the stopper to exert an increasing downward pressure on the stopper due to the difference in pitch of the threads, which further acts to provide sufficient lock-off pressure to insure the stopper being accurately and firmly seated against its seat so as to be capable of withstanding the pressure of the fluid to which T's of this type are normally subjected.

It will be understood that the several forms of the invention and method for controlling the flow of the supply through the main are merely illustrative of preferred embodiments, and that such changes may be made without departing from the spirit of the invention, as come within the purview of one skilled in the art and the scope of the appended claims.

I claim:

1. A T for connecting a fluid pressure main to a service pipe, said T having an axial bore and a lateral port and provided with an internally threaded end portion, said bore having a web provided with an axial opening and a seat, a stopper in the T arranged to engage said seat to cut off the flow of the fluid through the T, said stopper having an externally threaded stem, an externally threaded plug connected to the threaded portion of the T and having a central threaded opening connected to the threaded stem of the stopper, the internal threads on the plug and the external threads on the stopper being of different pitch than the external threads on the plug and the internal threads on the T, said stem having means for receiving a tool to move the stopper into and out of engagement with said seat, said plug having a tool receiving portion whereby when the stopper has been initially moved in firm engagement with its seat, and the plug is rotated relative thereto, the movement of the plug acts to exert a downwardly increasing pressure on the stopper due to the difference in pitch of the threads to insure the stopper being maintained in tight sealing engagement with its seat, and means on the stopper for engaging the wall of the opening in said plug when the stopper is moved away from said seat, to prevent the escape of fluid through said opening.
2. A T for connecting a fluid pressure main to a service pipe, said T having an axial bore and a lateral port and provided with an internally threaded end portion, said bore having a web provided with an axial opening and a seat, a stopper in the T arranged to engage said seat to cut off the flow of the fluid through the T, said stopper having an externally threaded stem, an externally threaded plug connected to the threaded portion of the T and having a central threaded opening connected to the threaded stem of the stopper, the internal threads on the plug and the external threads on the stopper being of different pitch than the external threads on the plug and the internal threads on the T, said stem having means for receiving a tool to move the stopper into and out of engagement with said seat, said plug having a tool receiving portion whereby when the stopper has been initially moved in firm engagement with its seat and the plug is rotated relative thereto, the movement of the plug acts to exert a downwardly increasing pressure on the stopper due to the difference in pitch of the threads to insure the stopper being maintained in tight sealing engagement with its seat, and said stopper having a tapered shoulder arranged to engage the plug to close the opening therein, when the stopper is moved to its full open position.

60

ELTING HENDERSON.
